UNITED STATES PATENT OFFICE.

HENRY G. BEUCKMANN, OF YOUNGSTOWN, OHIO.

DESIGN FOR A SCALE WEIGH-BEAM STANDARD.

SPECIFICATION forming part of Design No. 20,022, dated July 15, 1890.

Application filed March 24, 1890. Serial No. 345,169. Term of patent 14 years.

To all whom it may concern:

Be it known that I, HENRY G. BEUCKMANN, a citizen of the United States, residing at Youngstown, in the county of Mahoning and State of Ohio, have invented and produced a new and original Design for Scale Weigh-Beam Standards, of which design the following is a specification.

The accompanying drawing is a view in perspective of a scale weigh-beam standard in accordance with and illustrating my design.

The leading feature of my design consists in the shape of the standard comprising two side members or pillars which are united at their bases, and are thence curved first outwardly and then inwardly at their upper termini, at which they are spanned by a cap-piece, the whole forming a unitary standard, which, by reason of the peculiar curvature of its side members, presents the general appearance of a reversed heart.

Referring to the drawing, the standard is formed of two side members or pillars 1, the bases of which are united on the vertical center line of the standard. The side members are thence curved first upwardly and out-

wardly and thereafter upwardly and inwardly, and meet at top in the vertical center line of the standard, each being provided with an outwardly-curved extension 2 near its top. 30 The curvature of the side members is such that the standard has the general form of an inverted heart, the top of which is spanned by a cap-plate 3, connected to the upper ends of the side members and of their lateral extensions 2. 35

What I claim is—

The design for a scale weigh-beam standard, herein shown and described, the same comprising two side members united at their bases and thence curved first outwardly and then inwardly to an upper connection one to the other, substantially in the form of an inverted heart, and a transverse cap-plate connected to the point of the heart, as set forth. 45

In testimony whereof I have hereunto set my hand in the presence of two subscribing witnesses.

HENRY G. BEUCKMANN.
